UNITED STATES PATENT OFFICE.

TAKAYASU HARADA, OF KYOTO, JAPAN.

ALUMINUM ALLOY.

No Drawing.

Application filed June 4, 1924. Serial No. 717,845.

To all whom it may concern:

Be it known that I, TAKAYASU HARADA, a subject of the Empire of Japan, residing at care of Institute of Metallurgy, College of Engineering, Kyoto Imperial University, Kyoto, Japan, have invented certain new and useful Improvements in Aluminum Alloys, of which the following is a specification.

10 This invention relates to an alloy containing Cu: 0.3-6%, Ni: 0.5-6%, Mn: 0.5-6% the remainder being aluminum. The particular object of this invention is to produce an aluminum alloy resistant to weak acids, 15 solutions of salts and weak alkalis, having great hardness, strength and ductility.

The composition of this alloy is Cu: 0.3-6%, Ni: 0.5-6%, Mn: 0.5-6%, the balance being aluminum.

20 The method of manufacture is as follows—Prepare beforehand three “hardeners”, i. e. the first hardener is an alloy of Al:Cu:: 75:25, the second hardener is an alloy of Al:Ni:: 75:25, and the third hardener is an alloy of Al:Mn:: 75:25.

An amount of aluminum metal is first melted in a graphite crucible in a coke furnace at about 800° C., add the calculated amounts of the three hardeners in it, and agitate well with an iron rod. If they mixed homogeneously, take the crucible out of the furnace, put a little zinc-chloride on the surface of the molten alloy and take off the greater part of the slag, cool to about 700° 35 C., and cast in iron chill-moulds, to form slabs.

Rolling and pressing may be carried out as in the case of aluminum metal.

At present it is difficult to separate small 40 percentages of iron from aluminum. Its influence on aluminum are (1) it makes aluminum very corrosive, (2) it stains the surface of aluminum with black or dirty compounds when brought in contact with even weak organic acids or some salts, (3) it spoils the mechanical properties of aluminum. 0.3-6% of copper in this alloy 45 relieves all these ill-effects of iron perfectly, and promotes mechanical properties and resistivity to corrosion.

The alloy of aluminum and manganese is very resistant to corrosion and has a minute grain structure. Near the eutectic point of this alloy, the grains of the alloy 50 are evidently minute and do not grow larger even after long use.

Nickel in this alloy also has the same effect as manganese and copper and makes a more resistant alloy having a more minute grain structure than that containing no nickel.

As above mentioned, this alloy is almost absolutely non-corrosive when in contact with organic acids, solution of salts and alkalis (except caustic alkalis), and also in- 65 organic acids.

The examples of resistance to corrosion are shown in Table 1 and its mechanical properties are shown in Table 2.

TABLE 1.—Corrosion tests in some examples. 70

Analysis	(A)			(B)			(C)

N. B. * Shoyu is a kind of sauce made from common salt and yeast.

** Umezu is a kind of vinegar made from acid fruits, common salt and some vegetable.

Shoyu and Umezu are used in Japanese kitchen every day and are representative reagents which corrode kitchen wares.

corrosive when in contact with organic acids, weak alkalis and solution of many salts, and much more resistant to corrosion for inorganic acids or strong alkalis than other aluminum light alloys; (2) the grains of the alloy are very minute; (3) its mechanical properties are very superior; (4) impure aluminum ingots can be used to make this alloy.

10 As a result, this alloy is most suitable to make utensils which are used in contact with weak acids, alkalis or solutions of salts, especially for kitchenwares.

I claim:—

An aluminum alloy containing 0.3-6% ¹⁵ of copper, 0.5-6% of nickel, 0.5-6% of manganese, the balance being aluminum and impurities.

In witness whereof I have signed this specification in presence of two witnesses. ²⁰

Dated this 8th day of May, 1924.
